UNITED STATES PATENT OFFICE.

LEO DAFT, OF PLAINFIELD, NEW JERSEY.

INSULATOR-SUPPORT FOR ELECTRIC CONDUCTORS.

SPECIFICATION forming part of Letters Patent No. 396,196, dated January 15, 1889.

Application filed December 29, 1886. Renewed May 4, 1888. Serial No. 272,858. (No model.)

To all whom it may concern:

Be it known that I, LEO DAFT, a subject of the Queen of Great Britain, residing at Plainfield, Union county, State of New Jersey, have 5 invented certain new and useful Improvements in Insulator-Supports for Electric Conductors, of which the following is a specification.

My invention relates to that class of supports for electrical conductors mainly intended for overhead conductors for tramways, &c.; and my invention consists in means, fully set forth hereinafter, for connecting and insulating the supporting-hangers and for clamping 15 the conductors to the hangers.

In the drawings, Figure 1 is a side elevation in part section, showing two supporting-hangers for the parallel rails of an electrical conductor. Fig. 2 is a section on the line 12, 20 Fig. 1, looking in the direction of the arrow.

W represents any suitable support—as, for instance, one of the cross-bars or sleepers of the support of an overhead electrical conductor—and C represents the hanger pend- 25 ent from said support W, which hanger is turned up at the end to support the heavy electrical conductor 3, which, as shown, is a round wire or bar, but may be otherwise constructed.

30 In order to suitably suspend the hanger from the support W, I bolt to the under side of the support, by means of bolts G or otherwise, a plate, A, connected to or forming part of a bonnet or hood, J, the whole being formed of cast-iron or other suitable material.

35 The upper end of the hanger C is provided with a cross-head, 5, or otherwise constructed so as to receive securing-bolts D D, which pass through openings x in the cross-head, which openings are larger than the bolts to prevent contact between the latter and the cross-head, the said bolts extending into threaded openings in the plate A, and also through washers P, arranged between the 40 heads of the bolts and the cross-head, and through a plate or sheet, B, the latter and the washers being of vulcanized fiber or other suitable non-conducting material; and metallic washers 7 may be placed between the 45 washers P and the heads of the bolts, so as to prevent the washers P from being wounded

by the turning of the bolts. By this connection of the hanger with the support W, I firmly secure the hanger to the said support, so as to support the conductor in such manner as to resist the strains imparted to it by the traveling thereon of the moving trolley, and at the same time I effectually insulate the hanger from the parts to which it is connected and from the connecting-bolts and protect 60 the insulating material from storms, so that it will remain in a dry condition.

In order to detachably but firmly connect the conductor 3 with the hanger, I construct the latter with a stationary jaw, 4, and a 65 movable jaw, 5', each curved or recessed, so that when the jaws are brought together they will form a socket to receive the conductor, and in which it is securely clamped, the jaws being perforated for the passage of trans- 70 verse bolts 6, by means of which the movable jaw may be brought forcibly toward the stationary jaw and against the conductor in the socket. While the conductor is thus securely fastened, it may be readily detached at any 75 time by simply loosening the bolt 6.

While I have shown the parts above described as constructed to support two parallel conductors, 3 3, the same parts may be used in connection with a conductor consist- 80 ing only of a single rail or rod; but in either case the conductor is firmly supported, effect- 85 ually insulated, and is held in position upon the upturned ends of the brackets in such manner as to expose a continuous unbroken upper surface for the support and guidance 90 of the trolley.

It will be understood that the forms of the parts may be varied according to the particular character of the conductors and the positions in which they must be supported.

Without limiting myself to the precise construction and arrangement of parts shown, I claim—

1. The combination, with an overhead electrical conductor, and with a bracket supporting the same, of an overhead support, a bonnet secured to said support and receiving a cross-head of the bracket, and fastenings extending through the cross-head into the bonnet and through insulating material between the fastenings and the cross-head and between

the latter and the bonnet, substantially as set forth.

2. The combination of the support, pendent bonnet, bracket supporting a conductor and provided with a cross-head having openings x , bolts passing through said openings into the bonnet, an insulating material between the heads of the bolts and the cross-head and between the cross-head and the bonnet, substantially as set forth.

In testimony whereof I have signed my name to this specification in the presence of two subscribing witnesses.

LEO DAFT.
